UNITED STATES PATENT OFFICE.

ALEXANDER A. SUTHERLAND, OF DETROIT, MICHIGAN, ASSIGNOR OF TWO-THIRDS TO JOHN M. TODD AND EDWARD S. PALMER, OF DETROIT, MICHIGAN.

MACHINE FOR COMPRESSING PEAT OR OTHER MATERIAL INTO BRIQUETS.

SPECIFICATION forming part of Letters Patent No. 688,269, dated December 3, 1901.

Application filed April 6, 1901. Serial No. 54,597. (No model.)

To all whom it may concern:

Be it known that I, ALEXANDER A. SUTHERLAND, a citizen of the United States of America, residing at Detroit, in the county of Wayne and State of Michigan, have invented 5 certain new and useful Improvements in Machines for Compressing Peat or other Material into Briquets, of which the following is a specification, reference being had therein to the accompanying drawings.

My invention relates to improvements in machines for compressing peat and other material into uniform briquets, and especially to that class of machines having vertical compression-rams moving within self-discharging open-end molds and adapted to compress a fixed quantity of material, one charge superimposed upon another.

The object of my invention is to provide a machine of this character with a series of rams and a series of cam-wheels directly connected to and operating said rams, to provide mechanism for positively feeding the material into the molds, means for measuring the 20 quantity of material in each charge, means for preventing the heating of the molds by the consequent friction of compression, and to provide certain other new and useful features hereinafter more fully described, and 25 particularly pointed out in the claims, reference being had to the accompanying drawings, in which—

Figure 1 is a transverse vertical section of a machine embodying my invention on the 30 line 1 1 of Fig. 2. Fig. 2 is a side elevation of the same with parts broken away to show the construction. Fig. 3 is a horizontal section on line 3 3 of Fig. 1. Fig. 4 is a detail of the feeding mechanism. Fig. 5 is a detail 35 showing the stop-pin for limiting the action of the spring 34. Fig. 6 is a side elevation of the same.

1 is the driving-shaft, journaled on the vertical side frames 2 of the machine, and 3 is a second shaft journaled in bearings 4 on said frames. Gears 5 and 6 are mounted on these 40 shafts and transmit motion from the driving-shaft to the shaft 3. Mounted on the shaft 3 is a series of pinions 7, engaging gear-teeth 45 on the peripheries of the cam-wheels 8, which

wheels are mounted on a shaft 9, journaled in suitable bearings on the upper ends of the frames 2 of the machine. These cam-wheels are spaced a sufficient distance apart to allow the rams 10 to extend vertically between them, each of said rams being flattened and forked or slotted at its upper end to embrace the shaft 9 and, extending downward through the guide 11, is engaged at its lower end by a mold 12. The lower ends of these molds or 55 the molds proper consist of cast cylinders 13, made integral with a cast rectangular box or casing 14, extending across the machine between the side frames 2 and bolted thereto, and said cylinders 13 being in the vertical 60 center line of said box and a short distance apart the box or casing 14 forms a water-jacket around the molds. Into these cylinders 13 are inserted to take the frictional wear steel tubes 15, which may be removed 65 when worn by removing the bolts which hold the supporting-casting 16 in place.

On the tubes 15, near their lower ends, are secured collars 17, and the said casting 16 is divided longitudinally into halves and provided with apertures 18 to embrace the ends of the said tubes and collars and, extending across between the frames 2, is supported on lugs 19 on the frames, and the halves are also bolted together and flanged and bolted to the 70 bottom of the water-jacket. The casting 16 thus not only serves to secure the tubes 15 in place, but to support the molds and take the downward thrust of the rams. The rams are 75 made a close fit within the tubes 15 and are 80 projected into the same approximately only one-third of the length of the tubes, so that a number of the preceding charges remain compressed within each tube or mold and are only forced therefrom by the succeeding 85 charges, which in so doing are likewise compressed. That portion of each of said tubes which extends below the water-jacket is made with a slightly-increased internal diameter, so that the friction of the charge within that 90 portion is reduced and overheating of the tube prevented.

The upper ends or receiving portions of the molds are formed in the casting 20, which extends across the machine between the frames 95 100

2, and is bolted thereto and to the top of the water-jacket 14, and is also divided longitudinally, the halves being bolted together to embrace the rams.

5 To feed the material to be compressed into the molds 12, curved openings are provided in the side of the casting 20, and a curved cylindrical chute 21 is secured to said casting over each of said openings, each of which 10 chutes communicates with a hopper 22, secured to the guide 11, by means of a passage or throat 23, leading to an opening 24 in the top of the chute. A fixed shaft 25 is mounted on the frames 2, to the axis of which the chutes 15 are concentrically curved, said axis being in the horizontal plane of the tops of the tubes 15 of the molds, and longitudinally movable within each of said chutes is a feed-plunger 26, operated by an arm 27, loosely mounted 20 on said shaft 25, and upon each of said plungers is a longitudinally-movable sleeve 28, operated by an arm 29, also loosely mounted on said shaft. To operate each of the arms 27 and its plunger, an arm 30 is cast integral 25 with the hub of each of said arms 27, and bars 31, extending horizontally through and longitudinally movable in openings between the rams in the casting 20, are each provided with a vertical slot at one end to engage a 30 pin on each of the arms 30 and at the opposite end with a like slot to engage a pin on the end of each of the levers 32, which levers are pivoted upon the shaft 33, intermediate their ends, and turned thereon to actuate the 35 feeding mechanism by means hereinafter described. The arms 29 and the sleeves to which they are attached are actuated by means of springs 34, which are coiled around the hubs of the arms 29 and secured at one 40 end to said arms 29 and at their opposite ends to the arms 27, said springs exerting a force to hold said arms away from each other, and a stop-pin 35 on each of the hubs of the arms 27 is adapted to engage the arm 29 and limit 45 the action of said springs.

Inclosed within each throat 23 of the hopper is a measuring device for the purpose of determining the amount of material for each charge, consisting of a star-wheel 36, mounted 50 upon a shaft journaled in the sides of the throat, one end of said shaft being extended through the side and provided with a ratchet-wheel 37, adapted to be engaged by a pawl operated by a rod 38, each of said rods being 55 connected at its opposite end to one of the levers and moved longitudinally thereby.

The cam-wheels 8 are provided with ribs, forming two cam-grooves 39 and 40 on each of the adjacent sides, which grooves 39 are 60 engaged by rolls 41, journaled on the rams 10, and cam-grooves 40 are engaged by rolls 42 on the upper ends of the levers 32. The said cam-wheels are placed as near each other as practicable and allow for the free movement 65 of the rams, and each ram is provided with two rolls, one at each side, the adjacent sides of the wheels being provided with like grooves

to engage said rolls, and the levers 32 are similarly provided with rolls engaging cam-grooves, which are also alike on the adjacent 70 side of each pair of wheels. Any number of rams and their coacting parts may be used; but I prefer to use four, which are set on the quarter to equalize the strains and distribute the load throughout each revolution. On the 75 shaft 3 may be mounted one or more fly-wheels 43, if it is found desirable to do so.

The operation of my machine is as follows: The prepared peat or other material to be pressed into briquets is put into the hopper 80 and is fed into the chutes in predetermined charges, the spaces between the arms of the star-wheels forming pockets to receive and discharge a certain quantity of material, said wheels being turned one-fourth of a revolution 85 at each operation of the machine by the rods 38, the pawls carried by said rods being so positioned and arranged that the star-wheels are turned just before the plungers 26 reach the extreme outer end of their stroke. 90 The cam-grooves 39 are so formed that when the cam-wheels are in the position shown in Fig. 1 the ram operated by said wheels will be at the upper end of its stroke, as shown, with its lower end above the curved opening 95 into the feed-chute, and as the cam-wheels are turned in the direction indicated by the arrow said ram will be held in that position for nearly one-fourth of a revolution, the cam-grooves being concentric with the axis 100 of the wheel for that distance. The other portion of said cam-grooves is so arranged that upon the downward stroke said ram will move faster during the first part of its stroke and have a slow movement, with a consequent increase of power, at the lower or working end of the stroke, and is then again raised with a comparatively quick movement to the position shown in said Fig. 1. The cam-grooves 40, which operate the feeding mechanism, are so arranged that when the ram is in the position shown in Fig. 1 the lever 32 has 105 been moved and the plunger 26 projected into the chute, its inner end being about to enter the mold 12, and during the time that the ram 110 is held by the concentric part of the grooves 39 the inner end of the said plunger is projected into the mold to the top of the tube 15, forcing the charge downward therein underslight pressure, and withdrawn, leaving the mold 115 clear for the ram to descend and compress the charge just left. As the ram descends the plunger continues to withdraw from the chute, and the pin 35, engaging the arm 29, also withdraws the sleeve 28, thus opening 120 the passage from the hopper to admit the next charge, which will be deposited at the proper time by the star-wheel 36, as before described. When the feeding mechanism has assumed the position just described, with 125 the plunger and its sleeve withdrawn, it is held in that position for nearly a half-revolution of the cam-wheels, the cam-groove 40 being concentric for that distance, thus giv-

- ing the charge ample time to fall into the chute, and if it is found necessary there is ample time to admit of two charges or two pockets of the star-wheel being emptied.
- 5 The cam-wheels continuing to revolve, the eccentric part of the said grooves 40 will again engage the rolls on the levers 32, and the said plunger will be gradually projected into the chute, the spring 34 holding the arm 29 in engagement with the pin 35, and thus causing said sleeve 28 to move into the chute in advance of the plunger to close the opening 24 until said sleeve engages the casting 20 at its inner end and is stopped thereby, when 15 the said spring will yield to allow the plunger to continue its inward movement until its inner end reaches the horizontal plane of the axis of the shaft 25 or the top of the tube 15.
- 20 By the use of the feed mechanism described the feeding of a certain amount of material into the molds is insured, and by mounting the cam-wheels upon a common shaft and in a series, with only space enough between them 25 to allow of the free movement of the rams, each wheel having cam-grooves on each of its sides, a very compact construction is secured, and by driving each cam-wheel by gear-teeth on its periphery said wheels and the 30 shaft are relieved from much strain.
- What I claim as my invention is—
1. In a machine for the purpose described, a series of open-end molds, a series of gear-wheels mounted upon a shaft above said 35 molds, cam-grooves upon the adjacent sides of said gear-wheels, a series of rams adapted to move vertically within said molds and having forked upper ends to embrace said shaft, rolls upon each of said rams adapted to engage said cam-grooves, and pinions engaging 40 said gears.
  2. In a machine for the purpose described, having a series of vertical open-end molds, a removable tube in each of said molds, collars secured on said tubes near their lower 45 ends, and a casting having apertures to receive the lower ends of said tubes and collars, and hold said tubes within the molds.
  3. In combination with a machine for the 50 purpose described, having a series of vertical open-end molds, a casing around said molds forming a water-jacket and secured at its ends to the machine-frame, a removable tube within each of said molds having its lower end 55 extended below said water-jacket and formed with a slightly-increased internal diameter, collars secured on said tubes near their lower ends, a casting longitudinally divided into corresponding halves and provided with ap- 60 pertures to embrace the lower ends of said tubes, and lugs on the machine-frame to engage and support said casting.
  4. In combination with a machine for the 65 purpose described, having a vertical mold and a ram movable therein, a curved chute opening into said mold, and a curved plunger longitudinally movable within said chute.
  5. In a machine for the purpose described, in combination with a vertical ram and a vertical mold having a curved opening in its side, a curved chute secured over said opening, a curved plunger within said chute adapted to be projected into said mold, and means for operating said ram and plunger alternately. 70
  6. In a machine for the purpose described, having a series of vertical molds and rams within said molds, a segmentally - curved chute opening into each of said molds, a plunger of like curvature in each of said chutes 80 and adapted to be projected into said mold, a hopper above said chutes, passages connecting each of said chutes with said hopper, and means for operating said rams and plungers alternately. 85
  7. In a machine for the purpose described, having a series of vertical molds and rams, curved chutes opening into said molds, curved plungers within said chutes, a series of wheels having cam-grooves on their adjacent sides 90 to operate said rams, and a series of cam-grooves to operate said plungers.
  8. In a machine for the purpose described having a suitable frame, a series of vertical molds and rams, a shaft mounted on said 95 frame, a chute opening into each of said molds curved concentrically with the axis of said shaft, a plunger within each of said chutes, arms mounted on said shaft to operate said plungers, and means for operating said rams and plungers alternately. 100
  9. In a machine for the purpose described, having a vertical mold and ram, a curved chute opening into said mold and having an opening in its upper side, a hopper above said 105 chute communicating with said opening, a curved plunger in said chute, and a sleeve on said plunger within said chute.
  10. In a machine for the purpose described, having a series of vertical molds and rams, 110 curved chutes opening into said molds, each having an opening in its upper side, plungers longitudinally-movable in said chutes, longitudinally-movable sleeves on each of said plungers within said chutes, means for actuating said plungers, and flexible connections between said sleeves and plungers whereby said plungers when moved inward are preceded by said sleeves to close said openings in the top of said chutes. 115
  11. In a machine for the purpose described, having a series of vertical molds and rams, curved chutes opening into said molds, each having an opening in its upper side, plungers in said chutes, sleeves on said plungers, a 120 shaft mounted upon the machine-frame, arms journaled on said shaft to operate said plungers, springs to operate said sleeves in one direction, pins on said arms to operate said sleeves in the opposite direction, and means 125 for actuating said arms.
  12. In a machine for the purpose described, having a series of vertical molds and rams, curved chutes opening into said molds and

having openings in their upper sides, a hopper above said chutes communicating with said openings, plungers in said chutes, sleeves on said plungers, a shaft mounted on the machine-frame, arms journaled on said shaft and connected to said plungers, arms journaled on said shaft and connected to said sleeves, springs engaging at one end the arms connected to said plungers and at the opposite end to the arms of the sleeves and exerting a force to hold said arms away from each other, stop-pins on said plunger-arms to limit the action of said springs, and means for actuating said plunger-arms.

13. In a machine for the purpose described, in combination, a series of vertical molds, a series of vertical rams, adapted to move within said molds, a series of wheels having cam-grooves to operate said rams, curved chutes opening into each of said molds and having openings in their upper sides, a hopper communicating with said openings, a plunger longitudinally movable in each of said chutes, a series of levers pivoted on the machine-frame intermediate their ends and connected to said plungers at one end to operate the same, and at the opposite end provided with rolls adapted to engage cam-grooves in said wheels.

14. In a machine for the purpose described, a series of vertical open-end molds, a series of rams movable within said molds, a series of wheels provided with cam-grooves on their adjacent sides to operate said rams, a series of chutes opening into said molds and having openings in their upper sides, a hopper above said chutes, a passage connecting said hopper with said openings, a star-wheel within said passage, a series of plungers in said chutes, a series of levers pivoted intermediate their ends to the machine-frame and connected to said plungers at one end, rolls on the opposite ends of said levers adapted to engage cam-grooves on said wheels, and rods connected to said levers to actuate said star-wheels.

15. In a machine for the purpose described, having a series of vertical open-end molds, a series of rams vertically movable within said molds, rolls on the upper ends of said rams, a series of wheels having cam-grooves on their adjacent sides engaging said rolls, a curved chute opening into each of said molds and having an opening in its upper side, a hopper above said chutes, passages connecting said hopper and said openings, star-wheels in said passages, a plunger in each of said chutes, a sleeve on each of said plungers, a shaft mounted on the machine-frame, arms

journaled on said shaft to operate said plungers and sleeves, a stop-pin on each of said arms which operate said plungers, springs to hold the arms which operate the sleeves in engagement with said stop-pins, a series of levers pivoted to the machine-frame intermediate their ends, a bar having vertical slots in each of its ends connecting the lower ends of each of said levers with the levers to operate the plungers, rolls on the upper ends of the levers which are pivoted intermediate their ends and adapted to engage cam-grooves on the adjacent sides of the cam-wheels, and rods pivoted to said last-named levers and adapted to operate said star-wheels.

16. In combination with the frame of a machine for the purpose described, a driving-shaft journaled thereon, a transverse shaft mounted in bearings at the upper end of said frame, a series of cam-wheels having gear-teeth on their peripheries journaled on said transverse shaft, a series of pinions engaging said cam-wheels and a train of gears transmitting motion for said driving-shaft to said cam-wheels, a series of vertical molds arranged in a line transversely across the machine, a water-jacket surrounding said molds and secured to the frame sides, lugs on said frame sides, a casting supported by said lugs and secured to said water-jacket, a casting extending transversely between the frame sides and secured thereto and to the top of the water-jacket, forming an upward extension of said molds, and having curved openings in its side leading into each of said molds, vertical rams adapted to engage each of said molds, a guide for each of said rams secured to the said frame and extending transversely beneath said cam-wheels, forked upper ends on said rams embracing said shaft on which the cam-wheels are mounted, rolls journaled on said rams engaging cam-grooves on the adjacent sides of said cam-wheels, a hopper secured to said guide and communicating with said chutes, plungers longitudinally movable within said chutes, a shaft mounted on the machine-frame, arms journaled on said shaft to operate said plungers, levers pivoted on said frame, bars connecting said levers and arms, and rolls on the upper ends of said last-named levers and engaging cam-grooves on said cam-wheels.

In testimony whereof I affix my signature in presence of two witnesses.

ALEXANDER A. SUTHERLAND.
